UNITED STATES PATENT OFFICE

JULIUS DUNNER, OF NEW YORK, N. Y.

TAPERED-ROLLER FEATHER-PLUCKING DEVICE

Application filed May 9, 1928. Serial No. 276,253.

This invention relates to feather plucking devices and is an improvement of my invention disclosed in my pending application for Letters Patent, Serial Number 248,312, filed 5 January 21, 1928.

The main object of this improvement is to provide a device of the character described in my mentioned co-pending application which will be simpler in construction and 10 more efficient and perfect in operation.

Another object of the present invention is to make use of tapering or cone shaped rollers in a machine as characterized so that different speeds of plucking may be obtained at different portions of the tapered rollers, said rollers also permitting a gradually closer approach by the poultry, the feathers of which are to be plucked to the gripping portions of the roller, which will enable my novel 15 improved machine first to take the large and strong feathers of the poultry and afterwards finish the plucking operation by pulling out even the finest feathers or down on the body of the bird.

Still another object of this improvement is to provide rollers of the mentioned character, portions of which have been removed so as to permit an air suction or draft to intermittently blow through between the rollers 20 and draw the feathers therebetween.

Other objects of this improvement will be apparent as the specification of the same proceeds and among them may be mentioned: a curved outline given to the reduced portions 25 of the rollers so as to increase the suction between them and aid them in gripping the feathers therebetween; a novel arrangement and shape of the comb which in this device is applied only to a portion of the rollers and is gradually reduced and is gradually approaching said rollers; a new method of driving, whereby it is insured that the rollers will always run in phase.

With these and other objects in view, as 30 will more fully hereinafter appear, the present invention consists in certain novel details of construction and arrangement of parts, hereinafter fully described, illustrated in the accompanying drawings and more particularly pointed out and claimed, it be-

ing understood that various changes in the form, proportion, size and minor details of the device may be made without departing from the spirit or sacrificing any of the advantages of the invention. 55

In the accompanying drawings forming part of the specification:

Fig. 1 is a fragmentary longitudinal sectional elevation of my device, the section being taken on the line 1—1 of Fig. 2. 60

Fig. 2 is a front elevation of the same,

Fig. 3 is a detail showing the improved drive for the rollers;

Fig. 4 is another detail showing the journaling of the rollers at the opposite side to that of their drive; 65

Fig. 5 is a diagrammatical view of the rollers and comb placed before them,

Fig. 6 is a diagrammatical explanation of a modified form of the rollers, 70

Fig. 7 represents the full assembly of my machine, while,

Fig. 8 is a cross-sectional view of the preferred form of my tapered rollers shown in the position when their sides with the removed portions are facing each other and leaving a free passage between the two. 75

Similar characters of reference relate to similar parts throughout the drawings.

Referring now more closely to the drawings by characters of reference, the numeral 10 indicates the housing of my machine, preferably a metallic casing closed on all sides, except the upper front portion where an open space 11 is provided therein extending throughout the width of the machine. A pair of tapered rollers 12 and 13 is arranged across the lower part of the opening 11, the construction and arrangement of said rollers being described hereinafter. A partition wall 14 is provided across the width of the housing in the rear of the rollers, said partition dropping downwardly and then backwardly into branch 15 of the same and providing a confined passage 16 on the front and bottom parts of the space within the housing 10, said passage finally joining into the preferably circular conduit 17 in the rear of the housing 10. 85

Observing now Fig. 7, the assembly view 100

of my invention, the circular conduit or tube 17 leads into the housing of a fan or exhaust 18 of any suitable and well known make, said fan or exhaust being operated by the electric motor 18 through the intermediacy of a clutch 20. All the said mechanism is arranged on a table 21, preferably having a supporting frame or leg structure below the same (not shown) so that the whole device may form an independent unit and may be moved around as the necessity of its use may require.

I preferably employ a second electric motor 22 supported in a suitable manner on an appropriate member 23 of said leg structure, motor 22 to drive through a belt 24 the gearing generally indicated by the numeral 25 and designed to drive the rollers 12 and 13, as will be explained presently.

A comb structure, indicated in general by the numeral 26, is placed across the lower portion of the open space 11 in the housing, and in front of the rollers 12 and 13, the lower part 27 of said comb being full and solid while the upper part having the comb teeth 28 and the spaces 29 therebetween. A front wall 30 of the housing 10 preferably follows the taper of the rollers and so does the comb 26, as indicated in Fig. 5, said comb being larger or thicker at its end 31 where it faces the larger diameters of the rollers 12 and 13, and being gradually reduced in thickness towards the end 32 where it faces the smaller diameters of the taper rollers, preferably its distance from the rollers being also gradually reduced in the said direction. The rollers have the rounded trunnions 12^a and 12^b and 13^a and 13^b, respectively, wherewith they are journaled in the two side walls 10^a and 10^b of the casing 10, a portion of each roller is removed as at 12^c, 13^c, Figs. 1, 5 and 8, so that upon the rotation of the rollers part of the time their tapering portions are not meeting one another, but leaving a free space 33 between them. The lower roller 13 is journaled in a fixed manner, while the upper roller will be journaled in such a way as to permit a relative movement from its companion roller. For this purpose the trunnions 12^a and 12^b of the upper roller are arranged in the arms 34^a and 34^b (Figs. 3 and 4), freely movable in the recesses 35^a and 35^b, in the respective side walls 10^a and 10^b.

Ledges 36^a and 36^b are provided on the inside of the respective side walls, on which are hingedly secured the arms 37^a and 37^b carrying at their outer ends and within the slots 35^a and 35^b the arms 34^a and 34^b. The reason for this arrangement is that in case a large amount of feathers will be fed between the rollers 12 and 13 the upper roller 12 should be allowed to be raised somewhat, and with this aim in view filling pieces 38^a and 38^b are secured on the ledges in the rear of the movable arms 37, the two being connected by the

hinges 39 in the usual and well known manner. To normally secure the roller 12 in a close position on the roller 13, and to have a pressure between them necessary for their operation, a bolt 40 is secured into each of the ledges 36 carrying an adjustable spring 41 between the respective swinging arms 37 and the nut 42. The trunnions 12^b and 13^b are journaled in the side wall 10^b and in the usual manner, while the trunnions 12^a and 13^a are journaled in half bearings 43 and 44, as shown in Fig. 4, so that the said trunnions are actually running on one another and permit a close contact between the smaller ends of the tapered rollers.

The trunnions 12^b and 13^b at the larger ends of the rollers carry two identical cooperating gears 45 and 46, on the outside of the wall 10^b. The driving of this part of the machine is obtained from the motor 22, through a belt 24, as described hereinbefore, the upper belt pulley 47 having a gear 48 on its shaft 49 set into the wall 10^b, said gear cooperating with a larger gear 50 on a shaft 51, journaled in said wall 10^b and in a supporting arm 52 secured on said wall. The gear 50 is meshing with a further intermediate gear 53, said gear to drive the gear 46 and the gear 45 therethrough. A third gear 54 is also provided being entirely identical with the two gears 45 and 46, said gear 54 providing an independent second driving connection between the gears 53 and 45.

The operation of my device is as follows: The two electric motors 19 and 22 are set into motion and through them rotation is imparted to the fan or exhaust 18 and the gearing 25. The fan has an exhaust opening 55 and a current of air will be produced by the same entering through the opening 11 as indicated by the arrow 56, passing through the spaces 29 in the comb 26 and between the rollers 12 and 13, when the space 33 hereinbefore mentioned as occurring between them, said air current continuing its way through the conduits 16 and 17 to the housing of the exhaust 18 and passing out through the opening 55 as indicated by the arrows 57.

The gearing 25 will impart oppositely directed rotation to the rollers 12 and 13 as indicated by the arrows 12^d and 13^d, the tapered portions of said rollers being in contact under pressure while their full portions are meeting one another, while the space 33 is left between them at the moments when their reduced portions 12^c and 13^c are facing one another.

A bird, like a chicken or duck and so on, the feathers of which are to be plucked, is brought into close contact with the upper part of the comb 26 and manipulated there as necessity arises. The air current will lift the feathers off the body of the bird and will draw them between the two rollers, when the space 33 is produced between them. On the further

rotation of the two rollers the feathers between the full contacting portion of the tapered rollers will be drawn or plucked out of the body of the bird, resting against the teeth 28 of the comb and its skin protected from being torn from the same with the feathers the air current will draw the feathers through the conduits 16 and 17 and said current and the blades of the fan or exhauster 18 will further propel the feathers and finally expel them through the exhaust opening 55. A bag or other appropriate container may be attached to the opening 55 to receive the removed feathers.

As indicated in the drawings, removed portions 12^c and 13^c are preferably formed with a convexly curved outline, which, to my experience, will aid in producing an air current between said rollers and in gripping the feathers by them, though the rollers will also operate if their removed parts are severed from their main bodies by simple straight planes.

My device is also operated with full and complete rollers from which no portions have been removed and it will also operate with straight cylindrical rollers. I, however, prefer to employ rollers with partly removed portions for the reason indicated hereinbefore, and I also prefer to employ tapered rollers for the following reasons: The first operation in removing the feathers from the body of a bird has to do with its larger and stronger feathers, a stronger pull is necessary for the removal of such large and long feathers, but on the other hand they are easier to be brought between the rollers. For such starting operation I, therefore, will use the larger diameters of the rollers, nearer to the wall 10^b, and the comb will also have to be stronger and thicker at that point, but it may also be set at a somewhat larger distance from the rollers. After the first heavy feathers have been removed, the removal of the finer and shorter feathers is a more difficult operation and requires added care. The body of the bird has to be brought closer to the gripping surfaces at the contact points of the two rollers, therefore the diameters of the rollers must be smaller, the comb lighter and as near as possible to the rollers, therefore, I employ the tapering rollers and a gradually weakening comb approaching closer and closer to said rollers.

Finally, in order to enable the device to pluck the finest feathers from the body of the bird, no comb is provided in front of the shortest diameters of the rollers, close to the wall 10^a, so that the operator may put the body of the bird right close to the gripping surface between the two rollers.

My experience has been that rollers and combs constructed as described hereinbefore will enable the operator to pluck the body of a bird perfectly clean even of its finest feath-

ers with great speed and facility without any injury to the skin of the bird.

As a further assistance in securing a safe operation at the start of the plucking of the feathers, I also may employ a protecting cover 60 in the form of a plate hingedly secured to the top 10^c of the casing as at 61. I found it desirable to close this plate 60 down upon the comb when starting the plucking operation of a heavier bird, like a goose or duck, thereby limiting the amount of feathers gripped at the start by the machine to those within the space 62 between the side wall 10^b and the plate 60, as otherwise the machine will grip too large an amount of said strong and heavy feathers and tear part of the body of the bird therewith. After the heaviest feathers are removed plate 60 may be swung out of contact with the comb, and out from in front of the rollers to the top of the casing, and the plucking operation continued as desired.

The comb may have an inwardly projecting ledge 63 to support the feathers and to further protect the skin and body of the bird.

The specific gearing 25 is employed by me to insure that the rollers 12 and 13 will run in phase, that is their full and their removed portions always facing one another during their rotation, even if the upper roller 12 is lifted to a considerable distance, through a greater mass of feathers getting between the two. In such cases, gear 45 may be temporarily lifted out of mesh with the gear 46 and lose in phase in relation to the same. Even in such cases, however, the gear 54 will remain in mesh with the gear 45, and said gear 54 will be driven by the same gear 53 as gear 46 and being identical with said gear, it will keep on driving the gear 45 and the roller 12 with a uniform speed to that of the gear 46 and the roller 13.

In Fig. 6 I indicate a form of tapered rollers providing a combination of tapering and cylindrical roller operations. The upper roller 12' has a tapering portion 70 and a cylindrical portion 70^a, while the lower roller 13' has two different tapering portions 71 and 71^a. The diameters, angles and arrangement of the axes 70^b and 71^b of the rollers and their parts being such that the parts with the largest diameters at 70^a and 71^a will have an action similar to cylindrical rollers. In some cases I have found it best to start the plucking operation with such cylindrical rollers.

It will be obvious to those skilled in the art to which the invention relates that modifications may be made in details of construction and arrangement without departing from its spirit, hence I do not desire to limit myself in regard to such matters or otherwise than as the prior state of the art and the appended claims may require.

What I claim as new, is:

1. In a device for plucking feathers, a pair

of coacting oppositely rotating rollers for gripping the feathers therebetween, said rollers having portions of larger and smaller diameters, for operating on heavier and finer feathers, respectively.

2. In a device for plucking feathers, a pair of oppositely rotating rollers for gripping the feathers therebetween, having coacting tapering main portions, the first one of said rollers also having a cylindrical portion coaxial with the tapering portion thereof, and the second roller having a separate tapered portion to cooperate with said cylindrical portion of the first roller, being coaxial with the main tapered portion of its own roller.

3. In a device for plucking feathers as set forth in claim 1, intermediate portions of said rollers being removed to produce intermittent circumferentially closed free spaces between them while they are being rotated, and an air suction device in the rear of said rollers to draw the air through and the feathers into said spaces.

4. In a device for plucking feathers as set forth in claim 1, intermediate portions of said rollers being removed to produce intermittent circumferentially closed free spaces between them while they are being rotated; an air suction device in the rear of said rollers to draw the air through and the feathers into said spaces, the removed portions of said rollers having a convex curved outline to aid in gripping the feathers and in producing an intermittent air current between the rollers.

5. In a device for plucking feathers, a pair of coacting oppositely rotating rollers for gripping the feathers therebetween, portions of said rollers being removed to produce intermittent free spaces between them while they are being rotated, and one of said rollers having a fixed axis, while the other being resiliently movable on a pivoted arm towards or away from said fixed roller; a gear drive for said rollers to insure their running in phase, comprising a main driving gear, two identical coacting gears at the ends of the rollers, the one on the fixed roller being driven by the main gear, and a third identical gear adapted to coact with both, the main gear and the gear on the movable roller, in its normal and in its raised positions.

6. In a device as set forth in claim 1, the portions of the smallest diameters of the rollers being at one end of them and being continued in coacting trunnions, and two half bearings to journal said trunnions.

7. In a device of the character described two coacting rollers, and a hinged plate to cover part of the rollers when it is desired to limit the area of the operation.

8. In a device as set forth in claim 1, a hinged plate adapted to cover a part of the heavier portions of the rollers when it is desired to limit the area of their operation.

9. In a device of the character described, a plurality of rotatable tapering rollers for gripping feathers therebetween and a comb adjacent to the rollers for guiding the feathers thereto, said comb having gradually reduced thickness in the direction of the smaller ends of the rollers and said comb gradually approaching said rollers in that direction.

10. In a device of the character described, a plurality of rotatable tapering rollers for gripping feathers therebetween, and a comb adjacent to the rollers for guiding the feathers thereto, said comb having gradually reduced thickness in the direction of the smaller ends of the rollers and said comb gradually approaching said rollers in that direction, said comb only being arranged in front of the heavier portions of the rollers, for the purpose described.

Signed at New York, in the county of New York and State of New York, this 25th day of April, A. D. 1928.

JULIUS DUNNER.
